APPARATUS FOR SPOOLING HEELS

Merton W. Howard, Haverhill, Mass., assignor to
 Pope Machinery Corporation, Haverhill, Mass.,
 a corporation of Massachusetts

Application April 18, 1935, Serial No. 17,015

14 Claims. (Cl. 12—47.1)

This invention relates to the art of making wood heels and more especially to a method of and machine for performing a certain operation in the making of such heels known as spooling. 5 This consists in rounding and shaping the forward portions of the sides of the heel adjacent to the top lift so that the sharp edges or corners where the turned part of the heel joins the surface of the breast may be rounded off some- 10 what and made less prominent. This rounding off customarily varies from a maximum at the top-lift face of the heel to a vanishing point near the curve of the breast. For example, on a heel $2\frac{1}{2}$ inches in height, the rounding off 15 would extend about 2 inches from the top-lift face of the heel.

Wood heels are cut from blocks of wood in such a manner that the grain of the wood is substantially parallel to the longitudinal center line of the heel-seat plane. In shaping the sides of the heel in what is known as the turning operation, a rotating form cutter moves along the flanks of the block from the front to the back on each side in succession, this cutter making 20 a type of cut which can aptly be termed a whittling or stroking cut over that portion of the surface extending back from a plane defined by the widest transverse diameter of the heel-seat face and the widest diameter of the top-lift face. 25 The whittling cut is exemplified by the strokes of a pen-knife in sharpening an ordinary lead pencil. This kind of cut tends to stroke down the wood fibers and leave a smooth surface. On the contrary, the action of the turning cutter 30 on the portion of the heel's surface lying in front of said plane is to pick up the grain instead of stroking it down. This is an objectionable action 35 and often results in a rough or furry surface.

It is well understood that the direction of cut 40 relative to the direction of the grain is an important consideration in wood cutting. As has been shown, the direction of cut has a marked effect on the character of the cut surface. It is highly desirable that the surfaces of the turned 45 and spooled portions of the heel be uniform in smoothness and quality so that adhesives applied thereto may penetrate and act uniformly over the turned and spooled surfaces and so that the thin covering materials often used may 50 behave uniformly with relation to such surfaces.

Heretofore spooling has been done by scouring or abrading the heels on sandpaper wheels or rolls. More recently, spooling has been done more rapidly by a cutting operation in which 55 a pair of concave-faced form cutters cut pro-

gressively along the edges of the heel breast beginning at the top-lift end and ending well toward the heel seat, the cutters being guided by the turned surface of the heel. When the spooling cuts are made in this manner, the 5 surfaces left by the turning operation cuts and the spooling cuts are different in character since the former are whittling or stroking cuts while the latter are not. It is an object of the present invention to perform the spooling operation with 10 cuts of the whittling type so that the turned and spooled surface portions of the heel will be substantially uniform in character.

Demountable and replaceable top lifts for wood 15 heels have come into common use and on such heels it is necessary that the shape and size of the top-lift face of the heel be of the exact 20 shape and size selected by the designer and that this exact shape and size be maintained on all of the heels in the group intended to be capable 25 of receiving such top-lift replacements. There are often thousands of pairs of heels on which an exact shape and size of top is required, the success or failure of replaceable top lifts depending on the accuracy of reproduction of such 30 shape and size on each heel top.

Where spooling is done by holding a heel manually against an abrasive wheel, accuracy of size and shape of the heel top is practically impossible to obtain. Likewise, when the spooling is 35 done by cutters guided by the turned surface of the heel, any variations in the turned surfaces will be repeated in the spooling. Such variations are liable to occur, particularly near the top-lift end of the heel, due to the fact that heels are turned in a jack having several bearings 40 between it and the machine frame, and the top-lift end of the heel is the portion which is furthest from the jack supports. According to the present invention, the spooling cuts are reproduced accurately on the heels independently of the turned surfaces so that uniformity of size and shape of the spooled portion of the top-lift faces of the heels is assured, and the spooling 45 serves as a valuable check on the accuracy of the turning operation, since the failure of the turned and spooled surfaces on a heel to merge properly at once indicates a variation in the turning operation to be corrected.

Other objects will become apparent from the 50 following description, and from the drawings in which

Figure 1 is a side elevation of my improved 55 machine.

Figure 2 is a plan view of the same, with some of the jacks removed.

Figure 3 is a front elevation, with the complete multiple jack assembly removed.

5 Figure 4 is a side elevation of the jack assembly looking at the side opposite to that shown in Figure 1.

Figure 5 is a perspective view of a Louis heel before spooling.

10 Figure 6 shows the same heel after the spooling operation.

Figure 7 is a diagram showing the path followed by the cutters.

15 Figure 8 is a side elevation of a manually operated modification of my machine.

The machine comprises a base 10 having a shelf 12 on which a motor and speed-reducer unit 14 is mounted. A bed plate 16 is bolted to the top of the base 10. A hinged plate 18 is 20 pivoted at 20 to bosses 22 raised from the bed plate 16, to rock on a horizontal axis. The other end of the hinged plate 18 is connected by a connecting rod 24 to an adjustable-throw crankpin 26 carried on one end of the speed reducer shaft 28. A pivoted connection between the connecting rod and the hinged plate 18 is provided by the pin 30. Twin arms 32 are pivoted to the hinged plate 18 by vertical hinge pins 34. These arms are arranged to swing slidably on the plate 18 and are held in contact with the plate by their own weight and by lips 36 (Figures 1 and 3) which engage under the forward edge of the plate 18. On each of the arms 32 is mounted a motor-driven cutter-spindle assembly designated as 38, each assembly being adjustable relatively to its arm 32 about a vertical axis 40. Each assembly 38 includes a cutter-spindle and driving means therefor, belt-connected motors being shown on the drawings for this purpose. The 40 cutter-spindle assemblies are locked in the desired positions of adjustment by cap screws 42 inserted through slots 44. Graduations 46 assist in securing like settings of the twin spindles.

The arms 32 carry rollers 48 which ride on 45 respective cams 50, these cams being adjustably secured to cam carriages 52 by thumbscrews 54. The cam carriages 52 are slidably mounted on brackets 56 and are simultaneously and uniformly adjustable toward or away from the center 50 of the machine under the guidance of splines 59 by a collared right-hand and left-hand threaded rod 56 which can be operated by hand crank 58. The carriages may be clamped in adjusted position as by thumbscrew 53. Tension 55 springs 60 act to hold the rollers 48 in constant contact with cams 50.

The cutter spindles 62 carry removable form cutters 64. Between the cutters a heel-top support 66 is located, this support being adjustable 60 vertically by means of a bolt 68 through a slot 70 on a support lever 72 which is rockably mounted on the bed plate 16 by a hinge pin 74 so that the support 66 can be moved into and out of operative position. The upper end of the support 66 is cut away to form a step 75 to be engaged by the forward edge of the heel top. The lever 72 is provided with an arm 76 carrying a roller 78 which bears against a cam 80 mounted on the speed reducer shaft 28. A tension spring 82 acts to maintain the contact between the cam 80 and the roller 78.

The feeding portion of the mechanism comprises a wheel 84 rotatably and slidably mounted on a shaft 86 which is journaled at 88 in a bracket 90 which is bolted to the top front sur-

face of the bed plate 16. A setscrew 92 is provided to lock the wheel 84 against both sliding and rotary movement on its shaft 86.

The wheel 84 is fitted with a plurality of heel-supporting jacks 94, four being shown. Each 5 jack comprises a jack plate 96 disposed tangentially to the wheel 84 and adjustably bolted thereto by a bolt 98 inserted through a slot 100 in a bracket member 101 which projects from each plate 96 toward the shaft 86 and bears 10 laterally against a side of the wheel 84. Each jack plate 96 is fitted with an adjustable front stop 102, a fixed side clamp-jaw 104 and an adjustable spring-actuated clamp-jaw 106 (Figure 2), cooperating to position and clamp a heel 15 placed thereon. A disk 108, having as many radial slots 110 as there are jacks, is carried by the shaft 86 and is rotatively adjustable relatively thereto. A disk 112 is similarly carried by the shaft 86 (Figures 2 and 4). As hereinafter explained, the function of the disks 108 and 112 is to determine the adjusted position of the several jacks 94, uniformity of adjustment of the jacks being facilitated by individual angular adjustments of the disks 108 and 112 about the 25 shaft 86. After such adjustments of the disks 108 and 112, they must be secured so as to rotate as a unit with the shaft 86 during the operation of the machine. In order to secure the disks 108 and 112 in separately adjusted angular relation to the shaft 86, a thumbscrew 116 is tapped into and projects from a face of the wheel 84 parallel to the axis of the shaft 86. This thumbscrew extends through an arcuate slot 119 in the disk 108, but, as the disk 112 is not of the right 35 size or shape for a similar slot, a sector plate 115 of greater radius is permanently secured thereto and made virtually a part thereof. This sector plate has an arcuate slot 117 through which the thumbscrew extends. When the 40 thumbscrew is set up tight, the disk 108 and the sector plate 115 (and hence the disk 112) are secured in fixed angular relationship with the wheel 94 and the shaft 86, so that all of the elements carried by the shaft 86 then revolve 45 together as a unit. Pins 118 project laterally from the jack-plate brackets 101 through the slots 110 in disk 108, the pins having a close running fit in the slots, and sufficiently further to engage respective spiral cam surfaces 114 of 50 the disk 112. As hereinafter explained, these disks and associated members facilitate rapid and accurate adjustment of the several jacks when the jack assembly is being set up for operation.

A stop bar 120 forms an integral part of the heel-top support lever 72, and is movable into and out of the path of a series of abutments 122 on one side of a driving disk 124 which is fixedly mounted on the shaft 86. A series of stud and roller assemblies 126, one for each jack, is located on the opposite side of the driving disk 124. These rollers are adapted to be successively engaged by a latch 128 transversely slidable on the end portion of a plunger 132 and yieldingly pressed toward roller-engaging position by a spring 129. The plunger 132 is mounted for reciprocation in a housing 130 and carries a roller 134 at its other end bearing against a cam 136 mounted on the speed-reducer shaft 28. A spring 131 acts on the slide 132 to keep the roller 134 in constant contact with the cam 136. As indicated in Figure 1, the plunger 132 comprises two parts which can telescope a short distance against the pressure of a spring 138, thus pro- 75

viding a yielding cushion for the driving stroke of the latch 128. The telescoping movement of the two parts is limited by a pin 140 on one of the parts riding in a slot 141 in the other part.

5 A heel 142 is shown in Figure 1 in position to be cut. Another heel 144 is shown in process of being inserted into the following jack. A third heel 146 has been spooled and will be discharged from the jack into the work basket 10 when it comes into contact with an ejector bar 148 adjustably secured to the bracket 98 in the path of the heel 146 as the wheel 84 makes the next quarter turn. The breast of the heel engages the stationary bar 148 and is stopped 15 thereby while its jack continues on to the next position. The heel is thus removed from between the clamping jaws 104 and 106, and falls into a suitable receptacle (not shown).

In order to hold a heel steady and centered for 20 the spooling operation, a V-shaped support 150 is adjustably mounted on a lever 152 which is pivoted at 154 to the bracket 156 which is bolted to the bed plate 16 by bolts 160. An operating bar 162 is pivotally connected to the hinged plate 18 at 164 and is slidably inserted through a cross shaft 166 in the lever 152 with a fixed collar 168 below the cross shaft 166 and coil spring 170 in compression above it. As hereinafter explained, the support member 150 operates to 30 clamp a heel firmly against the support member 66 for the spooling operation.

To ensure accurate indexing of the jack assembly, the abutments 122 are successively pressed against the end of the stop bar 120 by a 35 pawl 172 pivoted at 174 to the bracket 98. The pawl 172 is pressed against the periphery of the driving disk 124 by a leaf spring 178 and is arranged to engage successive steps 176 in the edge of the disk 124 when the stop 120 is in contact 40 with an abutment 122. The face of each step 176 is preferably inclined for wedging action with the abutting end of the pawl 172. A hand wheel 180 is mounted on an extension of the speed reducer unit motor shaft.

45 In Figure 8 is illustrated a form of mechanism for positioning and clamping heels in place for the spooling operation, which is simpler than the automatic mechanism hereinbefore described. As shown, the connecting rod 24 is actuated by 50 a treadle 300 which is normally held in an elevated position by a tension spring 302. The heel-top support 66 is bolted to a carriage 304 and is vertically adjustable thereon, the carriage being slidable forwardly and rearwardly in suitable guides on an extension 306 of the bed plate 16. The carriage is readily moved to and held in any desired position by an adjusting screw 308. Pivotaly mounted on the carriage 304 is a lever 310, at the upper end of which a jack 312 55 is adjustably secured. The jack is provided with a bracket 314 which is clamped against the upper portion of the lever 310 by a bolt 316 which passes through the lever and through a slot 318 in the bracket 314. This permits both angular 60 and vertical adjustment of the jack. To limit the outward swing of the lever 310, a pin 320 may be mounted in the lower end thereof to engage a fixed lug 322 on the carriage 304.

In setting up for operation the automatic machine shown in Figure 1, it is necessary to adjust the several jacks 94 with relation to the shaft 86 so that each jack will be properly located with respect to the support members 66 and 150, when in the operating station, so as to cooperate properly with these support members. The adjustment

of the jacks will obviously depend on the size and shape of the heels to be spooled. In readjusting the jacks for operation on a new size or shape of heel, the driving disk 124, if not in the spooling position shown in Figure 1, is moved into that 5 position by means of the hand wheel 180 on the driving motor. Then the set screw 92 is loosened, permitting free movement of the jack assembly on its shaft 86 both rotatively and axially. The thumbscrew 116 is loosened, freeing disks 108 and 112 from the wheel 84. The bolts 98 in all four 10 jacks are loosened permitting free movement of the jacks on the wheel both angularly and radially and the breast stops 102 on the several jacks are loosened. One of the heels to be spooled is 15 pushed into the spring clamps on one of the jacks, and the heel and the entire assembly of jacks are turned over on the jack shaft until the top-lift face and breast face of the heel rest 20 snugly in the step 75 formed in the heel top support 66, the V support 150 having been first lifted manually against the action of compression spring 170 to permit the heel top to enter the step of the support, whereupon the support 150 is released 25 and is pressed by the spring 170 to clamp the 30 top-lift end of the heel firmly against the step 75. Since the V support is central relative to the cutters, the heel will be centered thereby regardless of its size. The jack assembly, being free to move axially on its shaft, allows this centering of 35 the heel on the machine by means of the V support. With the heel-seat end of the heel still clamped in the jack, the heel and jack can be moved up or down with the top-lift end of the heel still held tightly in the step on the top support, by the V support, until the angular position necessary to produce the desired spooling cut is found, upon which the setscrew 92 is tightened, locking wheel 84 to shaft 86, and the bolt 98 in the 40 particular jack being used is tightened. By the act of tightening this one bolt 98, the rotative position of the radially slotted disk 108 becomes 45 fixed to the jack wheel 84 by reason of the close running fit of the pins 118 in the slots 110 in the disk. Since the radial slots 110 are symmetrically arranged with reference to the shaft 86 and the jacks are counterparts of each other and are symmetrically pivoted on their respective bolts 98, any angular adjustment of any one 50 of the jacks about its pivot 98 by relative movement of the disk 108 will result in identical angular adjustments of the other three jacks about their respective pivots 98. In other words, the function of the disk 108 is to maintain at 55 all times a uniform angular relation between the several jacks and radii from the shaft axis 86 passing through the respective pivot axes 98. The next step is to rotate the cam disk 112 in a counter-clockwise direction as seen in Figure 4, until one of its cam surfaces 114 comes into contact with the pin 118 which is carried by the set-up jack, after which the thumbscrew 116 is tightened, locking the three disks 84, 108 and 112 together. The other three jacks are now 60 pushed in toward the jack shaft 86 until their 65 pins 118 also come into contact with cam surfaces 114 on disk 112, whereupon their locking bolts 98 are tightened. Since the cam edge 114 of the disk 112 comprises similar and symmetrically arranged spiral contours engageable by respective 70 pins 118, simultaneous engagement of the pins 118 and the cam 114 results in equal radial spacing of the jacks from the shaft axis 86 regardless of the position of angular adjustment of the disk 112 on the shaft 86. These three jacks will 75

now be located axially, radially and angularly to match the set-up jack. The breast stop 102 of the set-up jack is moved into contact with the set-up heel and tightened, after which the other 5 three stops 102 are adjusted to correspond with the first one, suitable scale markings (not shown) on the jacks being employed for this purpose. This completes the setting up of the multiple-jack assembly.

10 It will be seen that the general plan of setting up of this multiple-jack assembly is to first loosen all of the adjustments, and then, with a trial heel inserted into the jaws of one of the jacks, the heel still held in the jack can be positioned 15 in the machine for spooling, upon which that jack and the jack wheel are locked. Then the two auxiliary disks provide means for the instant like positioning of the other jacks. It is well understood that, in this class of machines, 20 facilities providing for the quick and accurate setting up of a multiple-jack assembly adds greatly to the value of the machine to the user by reducing the idle time of the machine.

After the jack assembly has been set up for 25 operation, the cutters 64 and their control cams may then be adjusted to perform the spooling operation properly on a sample heel. To this end, cutters of suitable shape to correspond to the profile of the turned surfaces are employed, and 30 the cutter-spindle assemblies 38 are adjusted, if necessary, relatively to the arms 32 about the pivots 40 so that the form shape of the cutters will match the curve of the heel along the initial lines of contact of the cutters with the sides of 35 the heel, the bolts 42 being loosened to permit such adjustment. Before starting experimental operation on the sample heel, the hand crank 58 is operated to retract the cam-carrier brackets 156 from each other so that the cutters will be 40 sure to cut away less material from the heel than is required for the complete spooling operation. The machine is then started, with the sample heel in position, and this heel is repeatedly operated upon, the cams 50 being moved closer together 45 each time by the hand crank 58 until the spooled surface merges smoothly and continuously with the turned surface of the heel. The machine is now ready for use.

As is evident from Figure 1, the initial lines 50 of contact between the cutters 64 and the sides of the heel, properly clamped between the support members 66 and 150, are in a plane approximately perpendicular to the top-lift face of the heel, one of these lines of contact being indicated at 330 in Figure 5. The cams 50 are of 55 such shape as to cause the cutters to follow paths such as are indicated at 332 in Figure 7. The horizontal components of these paths are produced by the cams 50 which swing the arms 32, 60 and the cutters 64 carried thereby, about the pivots 34 against the tension of the springs 60, as the cutters move up and down. The vertical components of the paths are produced by the rocking motion of the hinged plate 18 which 65 carries the arms 32 and the cutter assemblies, the rocking movement being caused by motion of the crank-pin 26 acting through the connecting rod 24. As a result of this movement 70 of the cutters, they perform the spooling operation by true whittling or stroking cuts so that the spooled surfaces are smooth like that major portion of the turned surface of the heel which has previously been shaped by whittling cuts made by the turning cutter as hereinbefore 75 described. It happens that the turned surface

areas of the slender part of the heel, which are shaped by the turning cutter when it is not making whittling cuts, that is, before the turning cutter has come abreast of the widest points of the top-lift face and seat face in each of its 5 front-to-rear cutting operations, are approximately coextensive with the areas which are cut away by the spooling cutters. Hence, according to the present invention, an effect of the spooling operation is to produce heels on the slender portion 10 of which substantially the entire flank surface is smoothly formed by whittling or stroking cuts. The cams 50 are preferably of such shape that the movement of the cutters at the moment of first contact with a heel, as illustrated in 15 Figure 7, is nearly vertical, so that spooled surfaces merge smoothly with the turned surface. After the cutters have been moved downwardly for a primary spooling cut, they move up again 20 along the same paths, thereby making a light finishing cut which results in an extremely smooth surface of accurate contour.

The machine is automatic in its action except for the insertion of the heels into the jacks. In 25 Figure 1, heel 144 is being inserted into the jack 20 by the operator while heel 142 is being spooled. Plenty of time for the loading is thus provided and there are no dangerous mechanisms near to the operator's hands. The heel slides easily into the jacks as the spring jaws need hold the heel 30 only lightly, the cutting stresses that are not balanced being taken by the top-lift support 66 and the heel-seat breast stop 102. Heel 146, as shown in Figure 1, has been spooled and will be discharged when its breast encounters the ejector 35 pin 148 during its travel in the next quarter revolution of the jack wheel.

The jack assembly is rigidly held during the pauses for spooling and loading by stop bar 120 in contact with abutment 122 and pawl 172 in 40 wedging contact with the angular face 176. The wedging contact insures complete freedom from looseness or play and also provides automatic compensation for wear. The diverging paths of the cutters above the line of contact with the 45 heel, as shown in Figures 3 and 7, provide clearance for the heel as it moves down into the spooling position. The timing of the heel and cutter is such that the cutters follow the heel as it approaches its spooling position and engage 50 the heel immediately after it has arrived at said position, the V-shaped support 150 being adjusted to grip the heel just before the cutters engage the heel. The movements of the V support are controlled by the movements of the hinged plate 55 18 which also carries the cutter assemblies. The connection is so arranged that, as the cutters move up and down, the V support is moved up and down also but at a greater speed and through a wider range, owing to the different dimensions 60 of the levers 18 and 152 which control the vertical movements of the cutters and the V support.

The indexing of the jack assembly is so timed with relation to the movements of the V support 150 that the heel to be spooled is moved into the 65 engagement with the support 66 when the support 150 is elevated, the latter being lowered to overtake the heel and engage it as it touches the support 66. Since the arm 152 on which the support 150 is mounted is rocked by rocking 70 movement of the table 18 through the connecting rod 162, the support 150 and the cutter 64 start their downward movements at the same time. The support 150, however, descends rapidly and reaches the heel before the cutters do. The table 75

18 with the cutters and the rod 162 continues its downward movement, but, since further movement of the support 150 is prevented by its engagement of the support with the heel, the result 5 is to compress the spring 170. This presses the support 150 firmly against the heel, causing the heel to be tightly clamped between the support 150 and the support 66 during the actual spooling operation which occurs as the cutters continue 10 their downward movement.

The automatic action of the heel jacking and supporting mechanisms is as follows. Immediately after the twin cutters have completed their finishing cuts on the heel, the cam 80 acts 15 through the lever 76, pivoted at 74, to withdraw the heel-top support 66 from the path of heel 142 and stop bar 120 from its contact with an abutment 122 on the driving disk 124. Then the cam 136 acting on the slide 132 causes the 20 latch 128 to engage a roller 126 on driving disk 124 and to rotate the jack assembly through 90° of travel to the next station at which the heel 144 will be in the position previously occupied by the heel 142 shown in Figure 1. Prior to the 25 arrival of the heel 144 at the spooling position, the heel-top support 66 and stop bar 120 have been returned to their positions as shown in Figure 1 by the tension spring 82 acting on lever 76 in cooperation with cam 80. The pawl 172 re- 30 engages the surface 176 and cooperates with the stop bar 120 to lock the driving disk and the jack assembly against any movement while heel 144 is being spooled and another heel is being inserted in the following jack.

25 The cam 80 is arranged to push the slide 132 toward the driving disk 124 slightly further than necessary to bring the abutment 122 into contact with the stop bar 120. This surplus movement is cushioned by the compression spring 138 to 40 prevent objectionable pressures being set up between the latch 128 and the rollers 126. The object of the surplus movement is to insure the firm seating of the abutment 122 against the end of the bar 120, and that the pawl 172 will 45 follow in on the inclined surface 176 to maintain in said firm seating during the spooling of the heel. This device also provides automatic compensation for wear on all of the parts acting to move the jack assembly from station to station and to hold the assembly rigidly at said stations. The spring 131 acts to return the slide 132 and the latch 128 into operating engagement with the next roller 126 while the spooling of the heel is occurring.

50 This organization as described provides simple but effective means for the safe handling of heels into the multiple jacks, the rapid but precise moving of the heels into the spooling position, and the subsequent discharge of the spooled 55 heels into a receptacle, all fully automatic except for loading, which occurs while the jack is standing still and at a safe distance from the cutters and other dangerous mechanisms.

55 The operation of the mechanism illustrated in Figure 8 is as follows. A heel is placed in the jack while the latter is swung out as indicated in dotted lines. Then the heel, still held in the jack by the hand, is swung into the spooling position as shown by the full-line drawings, whereupon the pedal 300 is pressed down and released to reciprocate the connecting rod 24, thus clamping, spooling and releasing the heel. The heel and jack, held all the while by the hand, are 70 then pulled back to the loading position, the

spooled heel is withdrawn from the jack, and a new one inserted.

It will be understood that the invention is not limited to the exact constructions shown and that deviations may be made therefrom without departing from the spirit or scope of the invention as defined in the following claims.

I claim:—

1. A machine of the class described, comprising a pair of spaced movable rotary cutters, a support, means for clamping a heel on said support, and means for moving said cutters through a cutting stroke in simultaneous engagement with the heel, said stroke being in a direction approximately perpendicular to the general height- 15 wise axis of the heel.

2. A machine of the class described, comprising a pair of movable spaced rotary cutters, a pair of adjustably fixed spaced cams, a support, means for clamping a heel on the support, and means for moving said cutters through a cutting stroke under the guidance of said cams in simultaneous engagement with the heel.

3. A machine of the class described, comprising a pair of spaced movable rotary cutters, a 25 pair of adjustable spaced cams, a support, means for clamping a heel on said support, and means for moving said cutters under the guidance of said cams into simultaneous engagement with the flanks of the heel, the movement being from 30 the back toward the front of the heel.

4. Mechanism for spooling a turned wood heel, comprising a pair of spaced movable convex-form rotary cutters, corresponding in part to the shape of the heel-turning cutters, a support, 35 means for clamping a heel on said support, and means for moving said cutters into simultaneous engagement with the heel, said engagement in its initial stage being tangent to the turned surface. 40

5. A machine of the class described, comprising a pair of spaced movable rotary convex-form cutters, a heel holder, means for moving said cutters into simultaneous engagement with the heel, and means independent of the heel for controlling the path of movement of the cutters 45 during said engagement.

6. A machine of the class described, comprising a pair of cutters, means for clamping a heel near its top-lift end, means for gripping the seat end of the heel, means for moving said gripping means to move a heel into and out of clamping position while gripped thereby, and means for causing relative movement between said cutters and said clamping means for operation on a heel 55 held by said clamping means.

7. A machine of the class described, comprising means for gripping a heel at its seat end, means for actuating said gripping means to move a heel into and out of an operating position while gripped by said gripping means, clamping means for seizing a heel near its top-lift end when in said operating position, and means for cutting said heel while held by said gripping means and 60 clamping means.

8. A machine of the class described, comprising a heel support actuatable to clamp a heel in position for a cutting operation thereon, and means for feeding heels step-by-step from a loading station into position on said support and from said support to a discharge station, said feeding means comprising a shaft, a circular series of heel holders revolvable simultaneously about the axis of said shaft to bring said holders successively into position adjacent to said heel 70 75

- support for cooperation therewith, means actuatable to adjust the holder in said adjacent position, and means facilitating similar adjustments of the other holders.
5. 9. A machine of the class described, comprising a pair of cutters, an intermittently rotating wheel having a series of heel-holding jacks and a corresponding number of cycles of movement separated by resting periods in each complete 10 rotation, automatic means for causing the cutters to spool a heel during the resting period, and automatic means for ejecting the spooled heel during the cycle of movement.
10. In a machine for performing a cutting operation on wood heels, heel-feeding mechanism comprising a shaft, a circular series of adjustable heel holders symmetrically arranged about said shaft, means for maintaining uniform adjustability of the several holders relative to radii thereto from the axis of said shaft, and cam means for facilitating uniformity of radial adjustment of said holders with respect to said shaft.
15. 11. A machine of the class described, comprising a pair of spaced movable cutters, a heel support adapted to hold a heel in operative relation to said cutters, and means for feeding heels into and out of position on said support, said feeding means including a rotatable wheel, 20 a series of heel holders adjustably mounted on said wheel, means for imparting step-by-step rotation to said wheel to bring heels carried by said holders into position to be operated on by said cutters, and means for moving said cutters along 25 their cutting paths during each dwell in the rotation of said wheel.
12. A machine of the class described, comprising a pair of spaced movable convex-form rotary cutters, corresponding in part to the shape of the heel-turning cutters, a heel holder, means for moving said cutters into simultaneous engagement with the flanks of a heel held by said holder, and means for guiding the cutters along predetermined paths in such a manner as to cut progressively along the side margins of the top-lift face of the heel, whereby the resulting contour of the top-lift face is independent of the shape of the cutters. 5
13. A machine of the class described, comprising a pair of spaced movable rotary form cutters 15 corresponding in part to the shape of the heel-turning cutters, a support, means for clamping a heel on said support, and means for moving said cutters into simultaneous tangential engagement with the turned flanks of the heel and for guiding the cutters to progress along the side margins of the top-lift face of the heel, whereby the resulting contour of the top-lift face is independent of the shape of the cutters. 20
14. A machine of the class described, comprising a pair of spaced movable convex-form rotary cutters, means for varying the angular relation of the cutter axes to one another without varying the spacing of the cutters, a support, means 30 for clamping a heel on said support, and means for moving said cutters into simultaneous engagement with said heel, the movement being in a direction from the back toward the front of the heel. 35

MERTON W. HOWARD.
